United States Patent

Des. 236,891
Patented Sept. 23, 1975

236,891

GUN HOLSTER

Kenneth A. Weissenburger, 46 Leamen Place,
Lynbrook, N.Y. 11563

Filed Aug. 22, 1974, Ser. No. 499,657

Term of patent 14 years

Int. Cl. D3—02

U.S. Cl. D22—13

Fig. 3

Fig. 5

Fig. 1

Fig. 6

Fig. 4

Fig. 2

FIG. 1 is a front elevational view of a gun holster embodying my new design;

FIG. 2 is a rear elevational view;

FIG. 3 is a top plan view;

FIG. 4 is a bottom plan view;

FIG. 5 is a left side elevational view; and

FIG. 6 is a right side elevational view.

I claim:

The ornamental design for a gun holster, as shown.
